Gupta, A. et al., "An Ornamental Design for a Cart," U.S. Appl. No. 29/731,529, filed Apr. 15, 2020, 32 pages.

Primary Examiner — Anhdao Doan

(74) *Attorney, Agent, or Firm* — McCoy Russell LLP

(57) **CLAIM**

The ornamental design for a cart key panel, as shown and described.

DESCRIPTION

FIG. 1 is a front-right perspective view of a cart key panel according to the claimed design.

FIG. 2 is a front view of the cart key panel.

FIG. 3 is a rear view of the cart key panel.

FIG. 4 is a right side view of the cart key panel.

FIG. 5 is a left side view of the cart key panel.

FIG. 6 is a top view of the cart key panel.

FIG. 7 is a bottom view of the cart key panel.

FIG. 8 is an enlarged view of the enclosed portion in FIG. 1.

FIG. 9 is an enlarged view of the corresponding enclosed portion in FIG. 6.

FIG. 10 is an enlarged view of the corresponding enclosed portion in FIG. 6; and,

FIG. 11 is an enlarged view of the corresponding enclosed portion in FIG. 6.

The dash-dash broken lines in the drawings illustrate portions of the cart key panel that form no part of the claimed design.

The dash-dot broken lines in FIGS. 1, 6, and 8-11 of the drawings showing the enclosed portions and section line form no part of the claimed design.

1 Claim, 11 Drawing Sheets
